ADJUSTABLE FASTENER

Paul Vorsteher, Vienna, Austria, assignor to Paul W. Werner Vorsteher Miederindustrie u. Gummiwebwaren, Vienna, Austria

Filed Dec. 15, 1959, Ser. No. 859,777
Claims priority, application Austria Dec. 22, 1958
7 Claims. (Cl. 128—501)

The invention refers to an adjustable fastener especially for both the back-pieces of brassieres comprising a strap having two or more elastic layers which transversally to their longitudinal extension and in certain intervals are integrally woven thus forming pockets lying side by side which may be engaged by hooks. Above all the invention is characterised in that bars are provided on the lines where the strap is integrally woven transversal to its longitudinal extension and that recesses are provided at the engaging parts of the hooks, or recesses are provided at the aforesaid stitching and projections are provided at the engaging parts of the hooks, said recesses being adapted for engagement by said bars or projections, respectively.

In the drawing the object of the invention is shown in several embodiments by way of example. The FIGS. 1 and 2 show straps which are each engaged by a hook. FIG. 3 represents the hook for itself. The FIGS. 4 and 5, 6 and 7, 8 and 9, as well as 10 and 11 respectively each show different woven straps and corresponding hooks. FIG. 12 is a further embodiment of said strap.

From FIG. 1 a strap 1 is to be seen which in a manner known per se on its left end may be connected to the back-piece of a brassiere. On the right end of the strap 1 an engagement with the back-piece 14 of the brassiere is effected by means of a hook 6. As may be seen, the hook 6 with its engaging part 5 engages a pocket which is formed by two woven lines 2. On the edge 10 the layers of the strap 1 are connected, too, so that here is given a pocket open only on one side at 9. Bars 3 are provided at the bottom of the woven lines 2. As may be seen from FIG. 1 the engaged hook 6 with its recess 7 closely engages the left part of the bar 3. Thereby a secure seating of the hook in the pocket of the strap 1 is granted. In this embodiment the bars 3 are provided on the left and on the right side of the woven line 2. If the bars 3 are arranged transversally to the woven line 2 are given a suitable dimension, almost completely closed pockets can be provided yielding a corresponding stiffening, see also FIG. 12.

In the embodiment according to FIG. 2 the bars 3 are arranged only on one side of the woven lines 2; otherwise this embodiment corresponds exactly to the embodiment according to FIG. 1.

FIG. 3 represents the hook 6 with the engaging part 5 and the holding hoop 12. The holding hoop 12 has a slot 15 with teeth 13 which when in use are pressed into the corresponding holding ribbon 16 of the back-piece 14.

On the base of these explanations the FIGS. 4 to 9 may be understood without further saying.

The FIGS. 10 and 11 show an inversion of the construction according to FIGS. 4 and 5. The bar 3 and the recess 7 (FIGS. 4, 5) are substituted by a recess 4 and a projection 8 (FIGS. 10, 11). For increasing the stiffening of the pockets formed the lower edge may be provided with a woven line 17 in the form of a bar.

The adjustable fastener according to the invention is extremely handy and very reliable. When in use the engaging part 5 of the hook 6 at the time is in close engagement with the woven line 2; by the elements 3, 7 and 4, respectively mentioned above a disengagement is safely voided. A tight seat is always granted by the strap 1

being elastic. The top 11 being propped against the woven edge 10 grants a good hold.

The invention is not limited to the embodiments shown. Of course, the bars and the recesses can have most different forms (curved, straight, pointed, and so on). The elasticity need not be yielded by the strap; for instance a connecting ribbon from the strap 1 to the pieces to be connected could be provided elastically. If hooks are provided on both the back-pieces to be connected said hooks can be engaged with the strap symmetrically; this goes only with symmetrically formed woven lines, however. The connections of the layers can also be provided in another form (for instance by integrally quilting, sewing, sticking, and so on).

I claim:

1. A connecting arrangement, particularly for releasably securing a brassiere to the body of a person, said arrangement comprising, in combination, a first member; a strap like second member of flexible material, said second member comprising at least two panels and transversely extending connecting means securing said panels to each other so that said panels form at least one pocket of predetermined length and having a closed end at one lateral side and an open end at the other lateral side of said second member, said open end permitting access to the interior thereof and a hook shaped coupling device having an attaching portion secured to said first member and finger means extendable into said pocket so as to bear against said connecting means and to prevent movement of said members in a direction away from each other and substantially perpendicular to said connecting means, the length of said finger means being at least equal to said predetermined length of said pocket so that the free end of the finger means may extend into close proximity of the closed end of said pocket, one of said means formed with at least one projection and the other of said means having an edge formed with at least one corresponding recess adapted to receive said projection when the finger means is inserted into said pocket whereby said second member is held against stirring on said finger means in the direction of said connecting means.
2. An arrangement as set forth in claim 1, wherein said connecting means is provided with a single projection in the proximity of the open end of said pocket and said recess is formed on said finger means.
3. An arrangement as set forth in claim 1, wherein each of said means is formed with alternating recesses and projections with the projections of said finger means receivable in the recesses of said connecting means and the projections of said connecting means receivable in the recesses of said finger means.
4. An arrangement as set forth in claim 1 wherein said connecting means consists of bars woven into the material of said panels.
5. An arrangement as set forth in claim 1, wherein at least a portion of at least one of said members consists of elastic material.
6. An arrangement as set forth in claim 1, wherein the length of said finger means is slightly less than the distance between the ends of said pocket.
7. A connecting arrangement, particularly for releasably securing a brassiere to the body of a person, said arrangement comprising, in combination, a first member of flexible material and comprising a loop shaped end portion; a strap like second member of flexible material, said second member comprising at least two panels and transversely extending connecting means for securing said panels to each other so that said panels form at least one pocket of predetermined length and having a closed end at one lateral side and an open end at the other lateral side of said second member, said open end permitting access to the interior thereof; and a hook shaped coupling

device having an attaching portion secured to said first member and finger means, said attaching portion comprising an internally toothed hoop receiving the end portion of said first member whereby the teeth of said hoop prevent shirring of said first member, and said finger means being extendable into said pocket so as to bear against said connecting means and to prevent movement of said members in a direction away from each other and substantially perpendicular to said connecting means, the length of said finger means being at least equal to said predetermined length of said pocket so that the free end of the finger means may extend into close proximity of the closed end of said pocket, one of said means having an edge formed with at least one projection spaced in inserted position of said finger means a predetermined distance from the closed end of said pocket and the other

of said means having an edge formed with at least one corresponding recess spaced in inserted position of said finger means said predetermined distance from the closed end of the pocket so as to receive said projection when the finger means is inserted into said pocket whereby said second member is held against shirring on said finger means in the direction of said connecting means.

CERTIFICATE OF CORRECTION

Patent No. 3,076,463

February 5, 1963

Paul Vorsteher

It is hereby certified that error appears in the above numbered patent requiring correction and that the said Letters Patent should read as corrected below.

In the grant, lines 2 and 12, and in the heading to the printed specification, lines 3 and 4, name of assignee, for "Paul W. Werner Vorsteher Miederindustrie u. Gummiwebwaren", each occurrence, read -- Paul u. Werner Vorsteher Mieder-
industrie u. Gummiwebwaren --.

Signed and sealed this 19th day of November 1963.
